UNITED STATES PATENT OFFICE.

WILLIAM HENRY REYNOLDS, OF HASTINGS, OKLAHOMA.

LINT DEFLECTOR.

Application filed January 18, 1924. Serial No. 687,154.

To all whom it may concern:

Be it known that I, WILLIAM HENRY REYNOLDS, a citizen of the United States, residing at Hastings, in the county of Jefferson 5 and State of Oklahoma, have invented a new and useful Lint Deflector, of which the following is a specification.

The present invention relates to a deflecting device to be employed in connection with 10 lint flues of gin stands to eliminate any possibility of the lint from the cotton, crowding at one end of the condenser, into which the lint passes.

Another important object of the invention 15 is to provide a device of this character which will evenly distribute the lint on its passage to the presser box, usually associated with the condenser disposed at one end of a lint flue, to insure an even bale being formed by the presser.

A still further object of the invention is the provision of an adjustable deflecting apparatus whereby the amount of air passing through the lint flue may be controlled so 25 that an even bat of cotton may be thrown into the condenser from one end to the other.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed, without departing from the spirit of the invention.

Referring to the drawings:

Figure 1 is an elevational view disclosing a lint flue and manner of positioning the 40 deflector forming the subject matter of the present invention.

Figure 2 is an enlarged sectional view through the discharge end of the lint flue.

Figure 3 is a sectional view taken on line 45 3—3 of Figure 2.

Figure 4 is a sectional view taken on line 4—4 of Figure 3.

Referring to the drawings in detail, the reference character 5 designates a lint flue 50 which is of the usual construction and through which the lint from the gin stands passes, pipes 6 being provided for establishing communication between the lint flue 5 and gin stands.

At the discharge end of the lint flue 5, is 55 the usual condenser 7 to which the lint

passes and from where the lint is taken to fill the press box 8.

It might be stated that with the lint flues now in use, it has been impossible for the 60 operators to control the flow of lint cotton to the condenser, the lint crowding to one end of the condenser, with the result that when the cotton enters the press box associated with the condenser, the presser forms 65 large ended bales which often breaks the press.

It is therefore an important object of the invention to provide a deflector which in the present showing is indicated by the reference 70 character 9, the deflector being in the form of a curved plate hingedly connected to a guard 10 that extends laterally from the base plate 11 which acts as a support for the deflector.

Bolts 12 connect the base plate 11 to the wall of the flue so that the base plate will be held against movement with respect to the flue. Supported on the rear surface of the member 9 is a bracket member 13 to which 80 the rod 14 is adjustably connected as at 15, the rod constituting an operating means whereby the member 9 may be moved with respect to the wall of the lint flue.

A suitable opening is formed in the wall 85 of the lint flue to accommodate the rod 14, there being provided a packing 16 around the opening to insure an air-tight connection between the rod 14 and lint flue.

Supported adjacent to the opening, is a 90 bracket 17 which is formed with a head 18 having an opening to accommodate the rod 14. A set screw 19 extends through the head and has its inner end disposed within the opening of the head where it contacts 95 with the rod 14 to secure the rod 14 in various positions of adjustment, when the deflector 9 has been properly positioned to accomplish its purpose.

From the foregoing it will be seen that 100 due to this construction, the lint and air passing through the lint flue may be controlled and the direction of travel of the air be changed to accomplish the better positioning of the lint in the condenser.

I claim:

A deflector of the class described comprising a supporting plate, a guard member formed integral with the supporting plate and arranged at an oblique angle with respect thereto, said guard being arranged adjacent to one end of the supporting plate. 110

hinge section mounted between the plate and obliquely disposed guard, a deflector carrying a hinge section at one end and adapted to cooperate with the first mentioned hinge section to pivotally support the deflector, a bracket member formed on the rear surface of the deflector and having an elongated

opening, and a rod having a bolt operating within the elongated opening to adjustably connect the rod and deflector.

In testimony that I claim the foregoing as my own, I have hereto affixed my signature

10

WILLIAM HENRY REYNOLDS
